CLAIM

The ornamental design for wireless earbuds and wearable charger and integrated speaker, as shown and described.

DESCRIPTION

FIG. 1 is a front perspective view the ornamental design for a first embodiment of wireless earbuds secured to a wearable charger and integrated speaker according to my invention;

FIG. 2 is a rear perspective view of the ornamental design for the first embodiment of wireless earbuds secured to a wearable charger and integrated speaker according to my invention;

FIG. 3 is a front view of the ornamental design for the first embodiment of wireless earbuds secured to a wearable charger and integrated speaker according to my invention; FIG. 4 is a rear view of the ornamental design for the first embodiment of wireless earbuds secured to a wearable charger and integrated speaker according to my invention; FIG. 5 is a side view of the ornamental design for the first embodiment of wireless earbuds secured to a wearable charger and integrated speaker according to my invention; FIG. 6 is an opposing side view of the ornamental design for the first embodiment of wireless earbuds secured to a wearable charger and integrated speaker according to my invention;

FIG. 7 is a top view of the ornamental design for the first embodiment of wireless earbuds secured to a wearable charger and integrated speaker according to my invention; FIG. 8 is bottom view of the ornamental design for the first embodiment of wireless earbuds secured to a wearable charger and integrated speaker according to my invention; FIG. 9 is a front perspective view the ornamental design for a second embodiment of wireless earbuds secured to a wearable charger and integrated speaker according to my invention;

FIG. 10 is a rear perspective view of the ornamental design for the second embodiment of wireless earbuds secured to a wearable charger and integrated speaker according to my invention;

FIG. 11 is a front view of the ornamental design for the second embodiment of wireless earbuds secured to a wearable charger and integrated speaker according to my invention;

FIG. 12 is a rear view of the ornamental design for the second embodiment of wireless earbuds secured to a wearable charger and integrated speaker according to my invention;

FIG. 13 is a side view of the ornamental design for the second embodiment of wireless earbuds secured to a wearable charger and integrated speaker according to my invention;

(Continued)

FIG. 14 is an opposing side view of the ornamental design for the second embodiment of wireless earbuds secured to a wearable charger and integrated speaker according to my invention;

FIG. 15 is a top view of the ornamental design for the second embodiment of wireless earbuds secured to a wearable charger and integrated speaker according to my invention; and,

FIG. 16 bottom view of the ornamental design for the second embodiment of wireless earbuds secured to a wearable charger and integrated speaker according to my invention. The broken lines are illustrative of environmental structure only and form no part of the claimed design.
